UNITED STATES PATENT OFFICE.

CHARLES McCCLAIR, OF SCHENECTADY, NEW YORK.

SAFETY STARTING MECHANISM.

1,135,385.

Specification of Letters Patent. Patented Apr. 13, 1915.

Application filed January 6, 1906. Serial No. 294,888.

To all whom it may concern:

Be it known that I, CHARLES McCCLAIR, a citizen of the United States, residing at Schenectady, county of Schenectady, and 5 State of New York, have invented a new and useful Improvement in Safety Starting Mechanism, of which the following is a specification.

My invention relates to starting means 10 for devices which must be started by some external or auxiliary source of power and which may start in the wrong direction.

It relates more particularly to starting devices for internal combustion engines, which 15 are usually started by hand, and which may back fire and start to run in the wrong direction, thereby damaging the starting device and often inflicting serious injuries on the operator who has hold of the starting 20 crank or similar starting member.

The object of my invention is to provide an improved safety starting means by which an internal combustion engine or similar device can be started without danger of injury 25 or damage in case the engine back fires and starts in the wrong direction.

Another object is to provide a safety starting means which cannot be moved backward by the engine but which can be easily moved 30 backward at will by the operator so that if desired the starting crank or member can be moved backward at any time to facilitate the starting operation, as, for example, where it is desired to permit the crank shaft 35 to oscillate once or twice during starting; and a further object is to provide a starting device which is in general an improvement on the starting devices heretofore commonly used.

40 My invention will best be understood by reference to the accompanying drawings, which show merely for purposes of illustration some of the various forms in which my invention may be embodied and in 45 which—

Figure 1, is a sectional view of an improved form of starting device especially adapted to an explosion engine; Fig. 2, is an end view of the starting device with the 50 starting crank in operative position; Fig. 3, is a view in perspective of the end of the engine shaft to which the starting crank is applied; Fig. 4 is a view of the starting crank. Fig. 5 is a sectional view, and Figs. 55 6 and 7 are end views of a modification of the form of device shown in Fig. 1.

An improved starting device for engines of this type is shown in Fig. 1. The shaft 13 is hollowed out, and in the space so formed is placed a rod 186. This rod is provided with a pin 187 which passes transversely through the rod 186. The rod 186 is threaded and carries nuts 188 and 189, which nuts engage a spring 190, which bears against the shoulder 191 formed in the shaft 60 13. The pin 187 extends through a spiral slot 192 in the shaft 13. A bracket 193 is secured to the frame work of the engine and carries a ring 194. On this ring are mounted pawls 195. A starting crank 196 70 is provided which has a safety device to prevent reverse rotation of the crank by the engine shaft. The particular form of crank illustrated carries a ratchet wheel 197, with which the pawls 195 engage. The starting 75 crank is best shown in Fig. 4, and comprises of a hub having a hollow therein which fits over the end of the shaft 13. The hub of the crank is provided with notches 198, which engage the pin 187. In using this 80 starting crank it is placed on the end of the shaft 13, so that the notches 198 engage the pin 187. As the crank is turned in the direction of the arrow the pin 187 has a tendency to travel along the slot 192. It is resisted 85 in this tendency by the spring 190 which is of sufficient strength to prevent the pin traveling along the slot 192, upon the application of a man's strength to the starting crank 196. In case the engine back fires, 90 however, the crank 196 begins to turn in the direction opposite the arrow in Fig. 4. The pawls 195 engage the ratchet 197 and lock the starting crank 196. As the shaft 95 13 continues to turn backward the force exerted on the pin 187 is sufficient to cause said pin to travel in the slot 192 compressing the spring 190. Eventually the pin 187 travels along the slot 192 such a distance that it goes out of the recess 198. When 100 this occurs the pin 187 moves along the surface 199 of the starting crank and as there is no longer anything to press the spring 190, said spring expands and through the pin 187 throws the starting crank to the 105 right and out of engagement with the pin 187, thereby protecting the operator from injury.

Fig. 5 shows a form of this device in which the spring is mounted on the starting crank, and the shaft 13 is solid. A casing 216 carries a sleeve 217, which fits over the

end of the shaft 13, and is provided with recesses which engage the pin in the end of the shaft. This sleeve slides on a central boss in the casing, and is held in position by 5 the bolt 218, which passes through a spiral slot in the sleeve. The sleeve is held in the position shown by a spring 227, which is strong enough to resist the strain of starting the engine. The casing 216 carries lugs 10 219 and 228, and a pawl 220 is pivoted to the lug 219. This pawl has attached thereto one end of a spring 221, the other end of which is attached a lug 222, carried by a crank 223, loosely mounted on a projection 15 224 of the casing 216. The crank is held in place on the projection by a nut 225. A pin 226 is attached to the crank in such position as to engage the pawl on the opposite side to that engaged by the spring. The lug 222 projects between the lugs 219 and 228, and is of less width than the space between the lugs, so that the crank 223 can be moved a short distance without the lug 222 engaging either of the lugs on the casing. The pawl 25 220 engages a ring 229 which is mounted on the engine frame similar to the ring 194 shown in Fig. 1. The inner side of this ring is formed in a series of steps as shown, with which the end of the pawl engages. 30 These steps are so formed that as the crank turns in the starting direction, as shown by the arrows in Fig. 4 and Fig. 6, the pawl slips over the steps, but when the sleeve 216 turns in the opposite direction, the pawl 35 engages with one of the steps and the reverse rotation of the sleeve is prevented. The surface of the steps with which the end of the pawl engages is formed as the arc of a circle of which the pivot of the pawl is 40 the center and the length of the pawl is the radius. As a consequence of this form of surface, pressure of the pin 226 against the pawl will result in a movement of the pawl toward the shaft, the end of the pawl sliding 45 along the surface of the step.

When the engine is to be started, the device shown in Fig. 5 is applied to the end of the shaft. The notches in the sleeve 217 engage with the pin in the end of the shaft. 50 As the device is turned in the direction of the arrow, the sleeve 217 tends to move toward the crank 223, owing to the engagement of the bolt 218 with the spiral slot in the sleeve. This movement is resisted by the 55 spring 227. If the engine backfires, the device tends to turn in the opposite direction, and the pawl engages the ring 229, and stops it. As the shaft 13 continues to turn backward, the spring yields, and the 60 device is released from the shaft. In starting an engine, it is often desirable to turn the starting crank backward at will while the crank shaft is stationary, or to permit the crank shaft to turn in the reverse direction, or to oscillate the crank shaft a few

times to draw in a charge. This may be done with this device, since when the crank is moved backward in the direction of the arrow shown in Fig. 7, the crank and sleeve 216 move relatively to each other and change 70 from the starting relation shown in Fig. 6 to the reversing relation shown in Fig. 7, the pin 226 depresses the pawl 220, out of engagement with the ring 229, and the safety device is thereby rendered inoperative, so 75 that as long as the reversing relation of the crank and sleeve is maintained the starting device, or the shaft to which the starting device is applied, can be turned backward as freely as though the safety pawl 220 were 80 not present and without disconnecting the starting device from the shaft. The protection against injury due to back firing is never lost, since as soon as the engine shaft turns faster in the reverse direction than the 85 starting crank the sleeve 216 moves relatively to the crank until their relative position becomes the starting position shown in Fig. 6, whereupon the pawl engages the steps on the ring 229 and further reverse 90 movement of the sleeve is prevented. As long as the shaft is turned as shown by the arrow in Fig. 5 the pawl is in engagement.

What I claim and desire to secure by Letters Patent is:

1. In an internal combustion engine, the combination with a starting crank having a handle, of a safety device for preventing reverse movement of said crank by the engine, and means for rendering said safety device 101 inoperative when pressure is exerted to turn the handle in the reverse direction.

2. A starting device comprising a sleeve for engaging the device to be started, an operating member for rotating the sleeve, a 105 safety device normally operative to prevent reverse movement of the sleeve, and means for rendering said device inoperative when pressure is exerted to turn the handle in the reverse direction.

3. In an internal combustion engine, the combination with a starting crank comprising a sleeve for engaging the engine shaft and an actuating handle movable relatively to the sleeve, of a safety device normally 115 operative to prevent reverse movement of the sleeve, and means actuated by a reverse movement of the handle relatively to the sleeve to render the device inoperative.

4. In an internal combustion engine, a 120 starting means comprising a shaft having a spiral slot therein, a pin in said slot with which a starting handle engages, and a spring which holds said pin in normal position at one end of the slot when subjected to 125 normal strain in starting, but yields and permits the pin to travel along the slot when the strain is abnormal.

5. A starting device for internal combustion engines comprising a sleeve carrying 130

two lugs, a second sleeve mounted concentric with the first and having a spiral slot for engaging a pin in the first sleeve, a spring between the sleeves tending to hold the second sleeve with the end of the slot against the pin, a crank loosely connected to the first sleeve and having a projection thereon which extends between the lugs, a pawl mounted on one of the lugs, a fixed rack to coöperate with said pawl, and connections between the crank and the pawl to cause the pawl to engage the rack when the crank is turned to start the engine and to disengage the pawl from the rack when the crank is turned in the reverse direction, whereby the engine may be turned in either direction by means of the crank.

6. A starting device comprising a starting member, a safety device for preventing reverse movement of said member, and an actuator coöoperating with said member and said device to move said member in either direction.

7. A starting device comprising a starting member, an actuator for moving said member, said actuator and said member being relatively movable to a limited extent, a safety device for preventing movement of said member in one direction and means responsive to relative movement between said member and said actuator for rendering said safety device inoperative.

8. A starting device comprising a rotatable member, a safety clutch member co-operating with said member to prevent reverse rotation thereof, a rotatable actuator connected to said member to rotate it in either direction, and means whereby a reverse movement of said actuator renders said safety clutch inoperative.

9. A starting device comprising a rotatable starting member, safety mechanism co-operating with said member to normally prevent reverse rotation thereof; an actuator for said member mounted to permit relative movement of said member and said actuator, and means whereby said safety mechanism is rendered inoperative by displacement of said member and said handle.

50. 10. A starting device comprising a starting member to be applied to the member to be started, safety mechanism for normally preventing movement of said starting member in one direction, and means for rendering said safety mechanism inoperative upon relative movement of said members.

11. A starting mechanism comprising a starting member constructed to engage the device to be started, a handle for rotating said starting member, a safety device for normally preventing reverse rotation of said member, and means controlled by said handle for at will rendering said safety device inoperative during reverse rotation of said handle and said member.

12. A starting mechanism comprising a starting member constructed to engage the device to be started, an actuating handle for positively engaging and moving said member in starting direction and movable relatively to said member in another direction, a safety device for normally preventing reverse movement of said starting member, and means actuated by movement of said handle in a direction other than the starting direction to render said safety device inoperative and thereby permit reverse rotation of said starting member at will.

13. A starting mechanism comprising a starting member constructed to engage the device to be started, an actuator for rotating said starting member in the starting direction, a safety device for normally preventing reverse rotation of said starting member, and manually controlled means for at will rendering said safety device inoperative while said starting member is in engagement with the device to be started and thereby permitting reverse rotation of said device and starting member at will.

14. A starting mechanism comprising a rotatable starting member constructed to engage the coöperating member on the device to be started, a sleeve concentric with said starting member having a connection therewith to positively limit relative rotation and relative longitudinal movement of said member and said sleeve and to produce when said member and said sleeve are relatively rotated a longitudinal movement of said member to disengage it from the coöperating member on the device to be started, and a safety device for preventing reverse rotation of said sleeve, said device being rendered inoperative at will by movement of said member.

15. A starting device comprising a sleeve member constructed to engage the shaft to be started and provided with a slot, a starting member having a hub freely movable relatively to said sleeve, and a pin on said hub extending into said slot to cause axial movement of said sleeve and hub.

16. A safety cranking device comprising a clutch member suitable for connection to the crank shaft of an engine, a normally idle coöperating clutch member adapted to interlock with said first clutch member when manually shifted longitudinally, a hand crank for operating said clutch members in the direction for starting the crank shaft of the engine, a ratchet and pawl safety device for holding the idle clutch member from rotation in the opposite direction, and resilient means connected to the first clutch member for permitting the disengagement of the clutch members by the power of the engine immediately after the engine has been started in the reverse direction by reason of backfiring.

17. A safety cranking device comprising a clutch member capable of being connected to the crank shaft of an engine, a coöperating clutch member adapted to interlock with the first clutch member, a crank for operating said clutch members in a direction for starting the engine, a ratchet and pawl safety device for holding said idle clutch member from reverse rotation, and means actuated by reverse rotation of said crank for holding said pawl out of engagement with said ratchet during reverse rotation of said crank.
18. A starting mechanism comprising a starting member capable of being rendered operative or inoperative at will, means for establishing between said starting member and the device to be started a connection constructed to remain rigid under normal starting strain but to yield under abnormal strain, and means actuated in response to the yielding of said connection to automatically render said starting member inoperative during reverse rotation of the device to be started.
19. A starting mechanism comprising a rotatable starting member movable longitudinally into inoperative position, and a normally rigid torque transmitting resilient connection between said starting member

and the member to be started constructed to permit relative movement of said members in response to abnormal strain and to move said starting member longitudinally into inoperative position in response to relative movement of said members.

20. A starting mechanism comprising a rotatable starting member mounted to move longitudinally into inoperative position and to remain in said position, a coöperating rotatable member engaged thereby and movable longitudinally out of operative relation thereto in response to abnormal thrust exerted by said starting member, and a spring for normally holding said coöperating member in a position to be engaged by said starting member and for permitting said coöperating member to move under abnormal pressure exerted by said starting member out of engagement with said starting member and into position to exert a longitudinal thrust to move said starting member longitudinally into its inoperative position.

In testimony whereof, I have affixed my signature in the presence of two witnesses.

CHARLES McCCLAIR.
